United States Patent

Des. 239,179

Patented Mar. 16, 1976

239,179

TELEPHONE LOCK

Terry M. Haber, 3050 S. Bristol, Apt. 8-C,
Santa Ana, Calif. 92707

Filed Dec. 9, 1974, Ser. No. 530,525

Term of patent 14 years

Int. Cl. D8—07; D14—03

U.S. Cl. D26—14 A

FIG. 1

FIG. 2

FIG. 3

FIG. 4

FIG. 5

FIG. 1 is a front perspective view of a telephone lock showing my new design;

FIG. 2 is a reduced rear elevation view thereof;

FIG. 3 is a right side elevation view thereof on the same scale as FIG. 2;

FIG. 4 is a front elevation view thereof on the same scale as FIG. 2; and

FIG. 5 is a rear exploded perspective view thereof.

I claim:

The ornamental design for a telephone lock, as shown.
